US00D842847S

(12) **United States Design Patent** (10) **Patent No.:** **US D842,847 S**
Walliser et al. (45) **Date of Patent:** **** Mar. 12, 2019**

(54) **ELECTRONIC DEVICE**

(71) Applicant: **Amazon Technologies, Inc.**, Seattle, WA (US)

(72) Inventors: **Marc Rene Walliser**, San Francisco, CA (US); **Troy Hulick**, Saratoga, CA (US); **Christopher Green**, San Francisco, CA (US)

(73) Assignee: **Amazon Technologies, Inc.**, Seattle, WA (US)

(**) Term: **15 Years**

(21) Appl. No.: **29/615,621**

(22) Filed: **Aug. 30, 2017**

(51) LOC (11) Cl. **14-03**

(52) U.S. Cl.

USPC **D14/240**; D14/358

(57) **CLAIM**

The ornamental design for an electronic device, as shown and described.

DESCRIPTION

FIG. 1 is a top perspective view of a first embodiment of an electronic device;

FIG. 2 is a bottom perspective view thereof;

FIG. 3 is a left-side view thereof;

FIG. 4 is a right-side view thereof;

FIG. 5 is a front view thereof;

FIG. 6 is a back view thereof;

FIG. 7 is a top view thereof;

FIG. 8 is a bottom view thereof;

FIG. 9 is top perspective view of a second embodiment of an electronic device;

FIG. 10 is a bottom perspective view thereof;

FIG. 11 is a left-side view thereof;

FIG. 12 is a right-side view thereof;

FIG. 13 is a front view thereof;

FIG. 14 is a back view thereof;

FIG. 15 is a top view thereof;

FIG. 16 is a bottom view thereof;

FIG. 17 is a top perspective view of a third embodiment of an electronic device;

FIG. 18 is a bottom perspective view thereof;

FIG. 19 is a left-side view thereof;

FIG. 20 is a right-side view thereof;

FIG. 21 is a front view thereof;

FIG. 22 is a back view thereof;

FIG. 23 is a top view thereof; and,

FIG. 24 is a bottom view thereof.

The broken lines depict portions of the electronic device which form no part of the embodiment in which they are shown.

1 Claim, 24 Drawing Sheets
